UNITED STATES PATENT OFFICE.

ADOLPH H. KOCH, OF LOS ANGELES, CALIFORNIA.

GAS BURNER AND MIXER.

1,130,984.

Specification of Letters Patent.

Patented Mar. 9, 1915.

Application filed June 9, 1913. Serial No. 772,695.

To all whom it may concern:

Be it known that I, ADOLPH H. KOCH, a citizen of the United States, and a resident of the city and county of Los Angeles, State of California, have invented certain new and useful Improvements in Gas Burners and Mixers, of which the following is a specification.

My invention pertains to burners, and it has special reference to gas burners which are particularly adapted for use in connection with stoves, furnaces, heaters and like appliances, and the object is to provide a burner which can be cheaply constructed, easily regulated, and which has a direct connection with a mixer so as to produce an efficient burner, as will now be set forth in detail.

In the accompanying drawings Figure 1 is a side elevation of the burner and mixer, showing the mixer in vertical longitudinal section. Fig. 2 is a top view of the burner and mixer, and Fig. 3 is an enlarged longitudinal section of the gas-ejecting nipple.

In carrying out my invention I provide a burner body in two parts or members, the lower member 5 having cast therewith a downwardly-projecting gas inlet tube 6, this lower member having on its under side a chambered projection 7 provided with holes 7* in its upper wall through which the gas is supplied through this chamber to the five ring channels of the burner body.

The upper member 8 of the burner is similar to the lower member 5, excepting that it has no chambered portion or inlet tube, and this member 8 has in its upper side a series of perforations 9 around each ring, as shown, for the discharge of the gas. The two plates thus described, are held together by screws 10.

The downwardly-projecting tube 6 has a right-angled, horizontally-disposed end, to which the mixer is attached. This mixer comprises a funnel-shaped member 11, with its reduced end 12 attached to the horizontal end of the tube 6, the base or large end of the member having two or more radially-projecting arms 13, the ends of the arms being connected to rim 13' provided with bolt holes to afford a means whereby it may be attached to a wall or partition, as shown, for instance, by the part 14, this funnel-shaped member being, therefore, on the inside of the stove or heater to which the burner is applied.

On the outer side of the wall 14 I attach a bell-shaped member 15, with a reduced inlet end 16, centrally. This member has exteriorly, at its base, radially-projecting ears 17, having bolt holes located so as to coincide with the bolt holes in the rim 13' of the funnel-shaped member, so that the same set of bolts 18 may be used to hold the two members 11, 15 together and to the wall 14. 65

A vertical inlet gas tube 19 passes through this bell-shaped member, the tube being threaded at both ends, and the upper end has a cup-shaped cap 20, while its lower end has a jam-nut 21 by means of which the tube 70 is rigidly held to the member.

The lower projecting end of the tube has attached thereto a valve member 22, one end of this member having a threaded bore to receive the threaded needle-valve stem 23. 75 The outer end of the stem has a hand wheel 24, and the stem is suitably packed, as at 25.

The perforated abutment 26 which receives the needle-valve is between the gas inlet end 27 and the vertical tube 19, and a small pipe is connected with the member 22 between the inlet end and the abutment, this pipe being designed to conduct fuel gas to a pilot burner, (not shown in connection with this application). 85

Within the bell-shaped member 15, and midway between the ends of the vertical gas pipe 19, is a gas-ejecting device, shown in detail in Fig. 3. This comprises a short nipple 30, with an axial duct 31, threaded 90 at its rear end, by means of which it is attached to the pipe 19, and its forward end is reduced. Back of the reduced end the body is threaded to receive thereon a tubular shell 32. The forward end of this shell 95 has an ejecting-duct 33, which is larger diametrically than the axial duct 31 of the nipple 30.

Radial holes 34 are formed through the wall of the shell 32 at a point near the forward end of the nipple 30. 100

This device is designed to eject the gas into the tube 6 which leads to the burner. I find that if the gas has a modicum of air mixed therewith in the manner shown, by 105 the nipple and shell, the quality of the flame produced is superior to the mixture produced by the mixing chamber alone, so that I regard the nipple and shell as a very important part of my invention. 110

The spaces between the radial arms 13 form air passages between the outside of

the funnel member 11 and the inside of the bell-shaped member 15 for admitting air to the interior of the combustion chamber from the air inlet 16.

5. The operation is as follows: When the gas is turned on and ignited at the burner, the heat produced in the combustion chamber in which the burner is located, causes a draft of air from the air inlet 16 through the bell-shaped member 15, and through the passages between the arms 13 into the combustion chamber. A portion of the air passing from the air inlet is crowded or forced by this action, past the nipple 30 and into the 10 conical member 11, wherein mixture is completed, the mixture then proceeding through the pipe 6 to the burner.

What I claim as new, is:

1. In a burner, a burner body, a mixer 20 attached thereto comprising a funnel-shaped member with radial arms, a bell-shaped member, larger diametrically than the funnel-shaped member and having means for attaching the same to the funnel-shaped member, said bell shaped member having a gas-ejecting nipple and mixer within, means for supplying gas through said nipple to said funnel-shaped member, and means for supplying air to said funnel-shaped member through said bell-shaped member.
2. In a burner, in combination with a stove or heater wall, a burner body, a mixer comprising a funnel-shaped member, with its reduced end connected to the burner and attached to the inside of the stove or heater 30

wall, a bell-shaped member diametrically larger than the funnel-shaped member attached to the enlarged end of said funnel-shaped member, the bell-shaped member having centrally a reduced air inlet opening, and discharge openings surrounding the funnel-shaped member, and a gas-mixing ejecting nipple within the bell-shaped member. 40

3. In a burner, a burner body, a mixer 45 comprising a funnel member with its reduced end connected with the burner body, a bell-shaped member, larger diametrically than the funnel member and secured to said funnel member, said bell-shaped member 50 being provided with a reduced inlet end and having discharge openings on the outer side of the funnel member, and a gas-mixing ejecting device within the bell-shaped member. 55

4. In a device of the character described, a funnel-shaped mixing chamber, a gas burner, a pipe leading from the small end of said mixing chamber to said burner, an air chamber communicating with said mixing chamber, means for introducing gas into said mixing chamber, and means for introducing air into said mixing chamber through said air chamber, said air chamber being provided with outlets to permit the 60 escape of exhaust air from said chamber. 65

ADOLPH H. KOCH.
